UNITED STATES PATENT OFFICE.

JAMES FENTRESS, OF CHICAGO, ILLINOIS.

WEAVING OR BRAIDING SHUTTLE SUPPORT.

1,363,858.

Specification of Letters Patent. Patented Dec. 28, 1920.

Application filed September 30, 1918. Serial No. 256,225.

To all whom it may concern:

Be it known that I, JAMES FENTRESS, a citizen of the United States, residing at Chicago, in the county of Cook and State 5 of Illinois, have invented a certain new and useful Improvement in Weaving or Braiding Shuttle Supports, of which the following is a specification.

This invention relates to machines for 10 weaving, and other related operations, but more particularly for braiding fabric on any sort of an object, such for instance as electric wires.

The object of the invention is to provide 15 a mounting for the shuttle carrying one thread, said mounting being so constructed that another thread which is to pass the shuttle, either through the simultaneous movement of both threads or the movement 20 of one thread while the other is stationary, may so pass the first thread without substantial friction which might injure the thread or retard the operation of the machine, or make an undue noise. A further 25 object of the invention is to provide a switching mechanism by which a plurality of threads successively passing or passed by the shuttle may be caused to alternately travel on opposite sides of the shuttle, thus 30 creating the successive over and underlapping of threads across the thread carried by the shuttle, as is always required in weaving or braiding.

The invention consists in means for carrying out the foregoing objects, which can be easily and cheaply made, which is satisfactory in operation, and is not readily liable to get out of order. More in detail, the invention consists in supporting the 40 shuttle on a multiplicity of relatively small, light, individual supports which singly do not seriously impede a passing thread, but which, in unison, have sufficient strength to properly sustain the shuttle. The invention further consists in switching mechanism for directing successive threads past the shuttle on opposite sides. More particularly, the invention consists in other features and details of construction set forth 45 hereafter in the specification and claims.

Referring to the drawings, in which similar numerals indicate the same parts throughout the several views.

Figure 1 is a side view of an ordinary 50 braiding machine of conventional construction, designed for braiding wire or the like 55

to which the device of this invention in its preferred form is shown applied.

Fig. 2 is an enlarged plan detail view of a shuttle mounting of this invention in its 60 preferred form.

Fig. 3 is a vertical sectional view, taken on the line 3—3 of Fig. 2.

Fig. 4 is a perspective view of the shuttle proper, removed from other supporting 65 parts of the device.

The braiding machine to which the device of this invention is shown applied consists essentially of a rotatable table 10, carrying a plurality of thread spools 12, rev- 70 oluble in one direction, and an annular ring table 14 supported on arms 16 and 18, revolvable in the opposite direction through the agency of suitable gearing 20 and 22 driven by a suitable source of power 24 in 75 the usual manner, forming no part of this invention. The resulting braid or braiding 26 produced by the machine is located at the top and is constructed from a plurality of threads 28 carried by spools 12 80 moving in one direction and a plurality of other threads 30 delivered from bobbins 32 carried in shuttles 34, suitably mounted in accordance with this invention in suitably formed recesses 36 formed in the ring 14 85 moving in the opposite direction. The recesses 36 in which successive shuttles are located are connected together by track-ways or passages 38, through which the threads 30 pass from one recess 36 to the next ad- 90 jacent recess 36. The number of threads 28 and 30 used in a given braiding operation is wholly immaterial.

In the particular embodiment of the invention, here illustrated, the shuttles 34 are 95 constructed as shown in detail in Figs. 2, 3, and 4, with longitudinal recesses or slots 40 extending along their sides which are entered and engaged by the ends of supporting springs, in the particular case here shown 100 wires 42, rigidly attached on the side walls of recesses 36 in ring 14 in some suitable manner. As shown in Fig. 2, they are secured through the agency of suitable adjusting screws 44, and the bobbin 34 has rigidly 105 attached to its rear end two other similar springs 48 which bear lightly at their ends 50 against the side walls of the recesses 36 in proximity to the entrance of the adjacent passage 38, heretofore referred to. As 110 a practical proposition, the springs 42—48 work best when placed as shown at about 45

degrees to the shuttle. The reason why these last mentioned springs 48 are secured as described is to prevent movement of the shuttle to the left, as viewed in Fig. 2, 5 through lagging back in movement of ring 14. All of the springs 42 and 48 are so arranged and constructed as to always position the shuttle, so that there are passages all around it for the passage of thread, as 10 hereafter described, notwithstanding the rotary movement of ring 14 with the shuttle therein. The springs may be made of any length and diameter, depending on the design of the details of the device by 15 which they are supported from the carrier 14.

The forward end of the shuttle 34 is pointed, as shown, and has pivoted to it a switch member 52 selectively locked in position by any suitable means, such for instance as the pointed plunger 54, controlled by a spring 56. When this switch is in the position shown in Fig. 2, a thread 28 passing from the right of Fig. 2 strikes the switch 25 and is first guided by it toward the lower side of the shuttle, as viewed in Fig. 2, whereupon, as thread 28 moves on, it throws the switch against the action of spring 56 in a clockwise direction until the forward 30 point 60 of the switch is in such a position that it is ready to guide the next thread which comes from the right of Fig. 2 along the upper side of the shuttle, as viewed in that figure, thereupon reversing the switch 35 and returning it to the position of Fig. 2.

Assume now that a thread is passing from the forward or switch end of the shuttle and moving to the left, as viewed in Fig. 2, it encounters one after another the successive 40 supporting spring wires 42, and moves each particular spring wire in succession out of notch 40 in the shuttle sufficiently to let the thread pass, and finally similarly moves end 50 of adjacent wire 48 to let it pass there. 45 In the particular case here illustrated, each shuttle is supported by ten wires 42 and positioned by two wires 48, so that the momentary nonfunctioning of one such wire as the thread passes does not interfere or perceptibly affect the sustaining of the shuttle 50 in operative position. The result of this construction is that threads are passed freely past the shuttle without in any way injuring the thread or disturbing the support of the shuttle and its contained bobbin. So little power is required to remove a single supporting spring or wire 42 from contact with the shuttle long enough to permit a thread to pass between that wire and 60 the shuttle that the machine is practically frictionless in so far as this part of the machine is concerned, and is also practically noiseless, due to the fact that each spring 42 moves through such a short distance to 65 permit the passing of the thread that no

appreciable sound is made as a given wire returns to place after the thread has passed.

As has heretofore been intimated, this shuttle mounting may be used in any sort of a machine in which one thread is required 70 to pass another, irrespective of the name of the machine, the kind of material worked upon, and the resulting product, without departing from this invention.

While the foregoing description only refers to the passage of a single thread at a time past the shuttle, the device will work just as well if more than one thread is passing on one side and if one or more are simultaneously passing on the other side of 80 the shuttle.

Having thus described my invention, what I claim as new and desire to secure by Letters Patent, is:—

1. In combination, a shuttle carrier, a shuttle and a plurality of spaced independent supports sustaining the shuttle, the engagement between each support and one of said first two mentioned members being one of contact only, whereby a thread may be 90 passed between one support at a time and the adjacent member.

2. A carrier member, a shuttle to be carried, spring members between the two, supporting one from the other, the engagement 95 of each spring member with one of the first two mentioned members being such that a thread may be passed between the two, as described for the purposes set forth.

3. In mechanism of the class described, a carrier member having a recess therein, a shuttle member positioned in said recess and clearing the sides thereof, a plurality of flexible supporting members sustaining the shuttle from the walls of the recess of the carrier member, the engagement of one end of each flexible member with the adjacent member first mentioned being such that a thread may be freely passed between the two, for the purposes set forth. 100

4. In mechanism of the class described, a carrier member, a shuttle member mounted in a recess in the carrier member and free from contact with the carrier member, a plurality of flexible springs extending from the 115 carrier member and entering a recess in the body of the shuttle member, said spring members being adapted for movement out of said recess by the passage of the thread between the carrier member and shuttle mem- 120 ber, for the purposes set forth.

5. In mechanism of the class described, a carrier member provided with a recess within which a shuttle may be mounted, there being passages leading to and from the recess at opposite ends, a shuttle member supported in the recess in the carrier member to permit passage of thread on either side of the shuttle member, and a switch mechanism adjacent to the forward end of the shuttle 130

member adapted to alternately switch successive passing threads entering the recess in the carrier member to alternate sides of the shuttle member, for the purposes set forth.

5 6. In mechanism of the class described, a carrier member having a recess therein for a shuttle member, there being passages leading to and from said recess, a shuttle member in said recess and clear of the walls thereof,

10 a switch at the forward end of the shuttle member adapted to successively switch thread moving from the adjacent passage into the recess first to one side and then to the other of the shuttle member, and a plurality of flexible supports along the sides of the recess of the carrier member, each detachably engaging the shuttle member in such a manner that the thread passing through the recess adjacent to the shuttle

15 20 may momentarily detach an end of a support from the member which it supports, thereby permitting the thread to pass, for the purposes set forth.

7. In a device of the class described, a carrier member made up of two ring shaped parts, lying in the same horizontal plane, the facing edges of which are spaced so as to provide recesses and channel ways, a shuttle mounted in one of said recesses clear of the walls thereof, a plurality of horizontal supporting spring members interposed between the shuttle and the adjacent wall of the recess in the carrier member, each such spring member being rigidly attached at one of its ends to the adjacent member, and frictionally contacting the other member, whereby a thread passing the shuttle member may successively slip past each adjacent supporting spring, for the purposes set forth.

In witness whereof, I have hereunto subscribed my name in the presence of two witnesses.

JAMES FENTRESS.
